UNITED STATES PATENT OFFICE.

WM. H. FORKER, OF MEADVILLE, PENNSYLVANIA.

IMPROVEMENT IN SECURING SHOES TO HORSES' HOOFs.

Specification forming part of Letters Patent No. 44,522, dated October 4, 1864.

To all whom it may concern:

Be it known that I, WILLIAM H. FORKER, of Meadville, in the county of Crawford and State of Pennsylvania, have invented a new and useful Improvement in Securing Shoes to Horses' Feet or Hoofs; and I do hereby declare that the following is a full, clear, and exact description thereof, which will enable any person skilled in the art to make and use the same, reference being had to the accompanying drawings, making a part of this specification, in which—

Figure 1 is a side sectional view of my invention, taken in the line *x x*, Fig. 2; Fig. 2, a horizontal section of the same, taken in the line *y y*, Fig. 1; Fig. 3, a transverse vertical section of the same, taken in the line *z z*, Fig. 2.

Similar letters of reference indicate corresponding parts in the several figures.

This invention has for its object the securing of the shoe to the foot or hoof without the use of nails, and at the same time obtain a secure fastening, and one which will admit of the shoe being readily attached to, and detached from the hoof.

To this end the invention consists in attaching to the upper surface of the shoe two jaws, each of which is provided with a flange, the jaws being attached at their rear ends to the back part of the shoe by means of pivots, and connected at their front ends by screws passing through the flanges, and held in position on the shoe by means of guide-pins or screws, all arranged as hereinafter set forth.

A represents a horseshoe, which may be constructed in the usual form and provided, when necessary or desired, with the ordinary toe and heel calks, *a b*. This shoe *A* has no holes made through it to admit of the passage of nails; but in other respects it may be like an ordinary horseshoe. On the upper surface of the shoe *A* there are secured two jaws, *B B*, each of which is in the form of a longitudinal half of the shoe *A*. These jaws are secured at their rear ends to the back part of the shoe *A* by means of screws or pivots *c c*, and the jaws, by means of this attachment, are ren-

dered capable of being moved or adjusted from and toward each other. The jaws are held snugly to the shoe *A* by means of screws or pins *d d*, which pass into the upper surface of the shoe and have their heads *e* fitted in slots *f*, made in the jaws *B B*, the heads *e* holding the jaws snugly down. The edges of the slots *f* are beveled to receive the beveled sides of the heads *e* and admit of the upper surfaces of the same being flush with the upper surfaces of the jaws, as shown in Figs. 1 and 3. Besides these screws or pins *d d*, for securing the jaws *B B* on the shoe *A*, the front of the latter is provided with a ledge or projection, *e'*, having beveled sides and fitting, when the jaws *B B* are closed, in recesses *g*, made in the ends of the jaws, and also provided with beveled edges corresponding to the beveled sides of the projection *e'*. Each jaw *B* is provided with a flange, *C*, which projects obliquely upward and inward from the outer edge of the jaws, so as to correspond with the inclination of the hoof. (See Figs. 1 and 3.) At the front end of each flange *C* there is a bracket or lug, *h*, projecting forward, and through these brackets or lugs screws *i* pass.

From the above description it will be seen that the flanges *C C* encompass the hoof of the horse, the bottom of the hoof resting upon the jaws *B B*, and that by screwing up the screws *i* the flanges will be made to press snugly to the hoof and firmly secure the shoe to it. Packing *j*, of leather, india-rubber, or any suitable material, may be interposed between the flanges *C* and the hoof.

Having thus described my invention, what I claim as new, and desire to secure by Letters Patent, is—

The two jaws *B B*, provided with flanges *C C* and secured to the upper surface of the horseshoe, and connected together, substantially as shown and described, for the purpose of securing the shoe to the foot or hoof, as set forth.

WM. H. FORKER.
